UNITED STATES PATENT OFFICE

2,367,125

METHOD OF MAKING MOTOR FUEL AND
BY-PRODUCTSJoseph Hidy James, Pittsburgh, Pa., assignor to
Clarence P. Byrnes, trustee, Pittsburgh, Pa.

Application October 3, 1939, Serial No. 297,713

17 Claims. (Cl. 196—50)

My invention relates to the manufacture of motor fuel for internal combustion motors and by-products from liquid hydrocarbons such as petroleum fractions; and involves partial oxidation of mineral oil or a fraction thereof and cracking as well as fractionating of the partial oxidation product.

One object of the invention is to reduce the cost of industrial products made from the partial oxidation product. For example, in making motor fuels by cracking of the partial oxidation product, their cost is reduced by extracting from the product of partial oxidation valuable chemical products of higher value per liquid unit than such fuels. These chemical products are preferably prepared from a fraction or fractions of the oxidation product of different average molecular weight than the motor fuel.

Another object is to better prepare the oxidation product for cracking to produce motor fuels; and another is to obtain cheaply and by relatively simple steps a motor fuel of relatively high octane value or rating.

Another object is to utilize portions of the oxidation product not well adapted for motor fuels, by preparing valuable industrial products therefrom.

In carrying out the process, mineral oil or a fraction thereof is partially oxidized, preferably in my vapor-phase process, by vaporizing, mixing with a gas containing free oxygen, and passing through a hot reaction zone preferably in the presence of an oxidation catalyst. During this vapor-phase partial-oxidation step some incidental cracking occurs and may be increased by increasing the temperature, the depth of catalyst if used, etc. The exit stream may be condensed and fractionated, and an intermediate portion may then be cracked, while industrial products may be extracted from the lighter fraction or portion. The heaviest portion or fraction or a part of it is preferably treated to produce detergents as hereinafter explained. I thus reduce the cost of the cracked intermediate motor fuel fraction or portion, since highly valuable chemicals are produced from the lighter and heavier fractions.

The partial oxidation and cracking steps may be successive in either order or substantially simultaneous, such as set forth, for example, in my United States Patents 1,597,796, 1,597,798, 1,716,272, 1,782,963, 2,010,085, 2,010,086, 2,036,215, 2,054,571, and 2,085,499. I prefer, however, to first oxidize and then crack a portion of the oxidation product, and remove acids between these

steps. The figure of the drawing herein shows in detail and in flow sheet form the step-by-step procedure of one form of my invention wherein by-products are formed in addition to motor fuel. In effecting partial oxidation, preferably in the vapor phase, although it may be carried out in the liquid phase, I preferably so grade the variables that a large percentage of alcohols is, in the example shown in detail in the drawing obtained, as disclosed in my United States Patents 1,759,620 and 1,859,587, with relatively less acids. The exit gas stream may be taken to and utilized in a polymerizing unit to make liquid motor fuel.

Following the partial oxidation step on "gas oil" for example, the condensed product is preferably treated to remove the free acids as, for example, by saponification with lime. In this step calcium hydroxide is added with water (5% by volume of oil) and warmed to 80° C. for four hours. The calcium soaps come out in the water layer in insoluble form and the acids are set free by treatment with a mineral acid such as hydrochloric acid. This step may, if desired, be combined with fractionation in accordance with United States Patent 1,948,161 to my assistant Bitler, the rough soaps being tapped out of the still; or the soaps may be separated and the remainder then fractionally distilled in the ordinary way. The acids may then be freed and recovered as free acids, if desired, and these may be sulfonated and converted into soaps.

If it is desired to obtain chemical products from a lighter fraction, I prefer as shown in the drawing to collect separately and cut out the first and lightest fraction up to about 10% of the total and boiling below about 200° C. This fraction may then be treated to obtain a good solvent preferably by dilute alcohol extraction in accordance with my United States Patents 1,782,963, 1,782,964, 1,835,600, or 1,894,097. In this case the oxidized oil after acid removal is distilled at atmospheric pressure to obtain a cut of about 10%; the extracting medium used is preferably a mixture of ethyl alcohol and water in the proportion of about 60% alcohol and 40% water. This may be applied in an ordinary extraction apparatus such as used for purifying lubricating oil and the volume of extraction mixture is about equal to that of the 10% cut. The alcohol and water mixture is then separated from the solvent by careful fractionation distilling. The extractive medium is then returned. About 30% of this solvent stock fraction is obtained as solvent and the remaining 70% may be added

to the main body of oxidized material used as cracking stock.

If, as I prefer, the heavy end portions of the oxidized material are to be made into chemical products, I preferably take this heaviest distilled fraction of about 15% which is above C₈ or C₁₂ and vacuum distil it. In this process about two-thirds becomes sulfate stock and the residue of about one-third, which may remain as "bottoms," may be added to fuel oil.

In the example flow sheet of the drawing, an Engler distillation showed the boiling range as follows, this showing when the 10% for solvent and the 15% for "heavy ends" occur. All temperatures are centigrade:

	Per cent
85°	Initial
188°	10
200°	13
235°	20
273°	30
298°	43
307°	50
317°	60
330°	70
337°	80
348°	90

The percentages show the volume passing over. In the preparation of sulfate stock (disregarding the 3% taken out as solvent), the distillation is stopped at 85% by volume so that the material to be vacuum distilled is above 343° C., distilling at atmospheric pressure. All above 343° C. is "heavy ends" which are vacuum distilled. Using a pressure of 5 centimeters of mercury the sulfation stock is distilled at approximately 80% under the Engler above given or from 263° C. to 276° C. The remainder is not distilled but is added to fuel oil.

The distilled-over portion is then treated with a polybasic acid of the inorganic type such as sulphuric acid, though other equivalent polybasic inorganic acids may be used such as boric acid, phosphoric acid, arsenic acid, and particularly those having three or more replaceable hydrogen atoms, as well as the corresponding "pyro" acids and the corresponding "ous" inorganic acids such as phosphorous acid, arsenious acid, etc. When sulphuric acid is used the treatment is preferably that set forth in my U. S. Patent No. 2,085,500 of June 29, 1937, from line 63, page 2, to line 39, page 3. This sulphonation step is now generally known. The product is a mixture of heavier esters or alkyl acid salts or acid esters, in the range above C₄ or C₆ and preferably above C₈.

On sulphating or treating with a polybasic acid for wetters and for detergents, and then neutralizing the alkyl acid salts such as sulphates, the sulphate soaps such as sodium alkyl sulfates are produced. The following is an example of sulfation used in the flow sheet diagram: Take 500 cc. of stock and 100 cc. petroleum ether (boiling under 90° C.) in a 1.5 L beaker. Surround the beaker with ice-salt mixture as temperature must be kept at 0° C. Using 20% oleum and a good stirrer, drop the oleum slowly into the cooled oil; it will take more than two hours, as the rate of oleum addition must be such that the temperature does not rise above zero C. A total of 166 cc. of the oleum is needed. After complete addition of oleum, stir (still keeping at zero C.) for one hour longer. Add 200 g. cracked ice (about size of olives and smaller),

stir for 15 minutes. When ice has melted add 40 g. of Glauber salt crystals, and stir for 15 minutes. If necessary warm until emulsion breaks. We have never had to heat about 50° C., and prefer not to go that high. Right here is where one must work as fast as possible as dilute mineral acid catalyzes the hydrolysis of the acid esters of sulfuric acid. Draw off lower layer. The top layer is now ready to saponify.

10 *Neutralization: formation of alkyl sodium sulfates or sulfate soaps*

To top layer above, add 100 cc. water and 400 cc. of the petroleum ether. Stir in pulverized soda ash until slightly on alkaline side.

15 Make sure of saponification by stirring for one-half to one hour longer, making other additions of soda if necessary. Add with stirring 25 cc. denatured alcohol (formula 1) to facilitate separation. Three layers form. Lowest: contains saturated solution of sodium sulfate with the slight excess of sodium carbonate. Intermediate: soaps in solution with part of the inorganic salts. Top: non-sulfatable oil plus the added petroleum ether. Draw off: test top layer for soap by extraction of a test sample with 50:50 alcohol water medium, evaporating off alcohol and examining for soap. If there is a sufficient amount of soap present, extract this whole layer with successive portions of 50:50 as above. This is usually not necessary. If it is done, the extracted soap solution must usually be washed with the petroleum ether to remove any oil. A test portion of the extracted soap having all the alcohol evaporated should give a clear water solution, showing that all the oil has been removed.

The main soap solution layer above (the intermediate layer) is given successive petroleum ether (under 90° C.) washes until any oil is removed. This can be told by the color of the petroleum ether, and checked by taking a few cc. of the soap solution for a test sample, evaporating off the alcohol and noting if the soap dissolves in hot water without turbidity. If soap is recovered from the petroleum ether layer above and it is free from oil it may be added to the main portion of the soap at this point.

The soap solution should now be evaporated 50 carefully to a pasty consistency, if the removal of the sodium sulfate is desired. Use about 60° C. as the upper limit of temperature and evaporate with plenty of air blowing over the surface of the solution. The foregoing pasty solution is now 55 diluted with ten volumes of denatured alcohol which takes the soaps into solution and throws out the sodium sulfate. Filter, and evaporate carefully to obtain the dry soaps. The yield of sulfate soaps based on the sulfated oil used varies from 25% to 50% by weight.

60 In these steps the non-sulfatable oil remaining which is usually the larger portion thereof is separated and added to the cracking stock.

The cracking stock is then subjected to a cracking operation or thermal decomposing step 65 either with or without a catalyst and with or without superatmospheric pressure, but preferably under moderate or heavy pressure. This may be done either in the liquid phase or vapor phase or both combined. In cracking, the range 70 of the oxidized stock was from 180° C. to 350° C.; the cracking pressure may be 250 lbs. per sq. in., the temperature about 931° F., and the coil volume in cu. ft. above 750° F. per barrel throughput per day—about .030. In this opera-

tion a high octane rating gasoline is produced; the gas produced may be polymerized into "polymer" gasoline, and the remainder may be utilized as "recycle stock" to which fresh oil ("make-up") is added to go to the oxidizer. An example of gases from cracking this oxidized mixture shows CO_2 —2.3%, CO —29.4%, H —2.4%, methane—17.8%, ethane—12%, ethylene—12.5%, propane—6.6%, propylene—10%, butanes—2.6%, and pentanes—4.4%. This analysis plainly shows that this gas mixture is amenable to ordinary types of polymerization used in gasoline forming. The above specific directions give one example of the process—that shown in the accompanying flow sheet drawing; and the claims herein are not limited thereto.

In the figure of the drawing I show an example of one form of my process, giving approximate figures and proportions wherein 20,000 barrels of gas oil are partially oxidized, preferably by my vapor phase process, giving about 90% of condensed product. Of this about 50% goes into motor fuel, about 14% into by-products, about 4% into gas loss, about 5% into fuel oil, and about 10% into loss in oxidation, the remainder going to "recycle stock."

Thus certain lighter and heavier oxygen derivatives of hydrocarbons formed in the oxidation step may be made into industrial chemical products of much higher value per unit than motor fuel, or any desired proportion of the total may be passed on into the cracking step for making motor fuel and other products. By using a bubble tower succeeding the oxidizer, the exit stream therefrom may be fractionally condensed into the desired fractions, which may then be treated as above recited.

A modification of the foregoing procedure is to remove the solvent from the total oxidized product just after the removal of the acids as outlined above, but then take all the remainder of the oxidized oil, except the 5% heavy ends, to the cracking process. In all cracking processes, whether pyrolytic or catalytic, there is a broad fraction which runs in boiling points from the upper end of gasoline through to the ordinary gas oil end point. This is usually known as "recycle stock," but for my by-product purposes, I may first sulfite either the whole fraction or preferably the heavier portion, making the usual sodium alkyl sulfates or "sulfate soaps." The non-sulfatable oil becomes the "recycle stock" in this modification. One advantage of this modification is that the unsaturated compounds formed in the cracking operation become available for sulfation, thus increasing the sulfate soap yield over that outlined in detail in the drawing.

The advantages of my invention result from the utilizing of different portions of my oxidized product which are of different average molecular weight, for conversion into chemical products and liquid fuels respectively; and from the elasticity of operations thereby obtained. Depending upon the demand, prices, etc., the steps may be varied and the proportions produced for various industrial purposes. The cracked motor fuel product usually contains oxygen derivatives of hydrocarbons which aid in burning qualities and value, while derivatives of other molecular weights are made into valuable chemical products.

The partial oxidation may be carried out either in the vapor phase or liquid phase or both, the fractionating may be carried out in different ways, the fractions may be varied as to end points, the acids may be removed before fractionating,

or taken out of certain fractions after fractionating, the heaviest portions may be removed after cracking, and many other changes may be made without departing from my invention.

5. I claim:

1. In the treatment of a product of the partial oxidation of mineral oil containing non-aromatic hydrocarbons, the steps consisting of partially oxidizing mineral hydrocarbons in the presence of free oxygen into a plurality of different oxygen derivatives of aliphatic hydrocarbons in the range from alcohols to oxygenated acids, fractionating the product, cracking a fraction and polymerizing 1350,3 gases from the cracking step.

15. 2. In the treatment of a product of the partial oxidation of mineral oil containing a plurality of different oxygen derivatives of aliphatic hydrocarbons in the range from alcohols to oxygenated acids, the steps consisting of separating the product into portions of different average molecular weights, reacting a heavier portion with a chemical to obtain a chemical product therefrom, adding a remaining part of said heavier portion to a lighter portion and cracking the combined portions.

25. 3. In the treatment of a product of the partial oxidation of mineral oil containing non-aromatic hydrocarbons, the steps consisting of fractionating the liquid product into fractions of different 30 average molecular weights, extracting chemical products from a lighter fraction and applying a chemical reagent to extract a chemical product from a heavier fraction remaining after said extraction, adding parts of said fractions to an intermediate fraction, and cracking said combined fractions. X 1319

35. 4. In the treatment of a product of the partial oxidation of mineral oil containing a plurality of different oxygen derivatives of aliphatic hydrocarbons in the range from alcohols to oxygenated acids, the steps consisting of fractionating the liquid product, reacting with a chemical to extract a chemical product from a lighter fraction, returning a remainder thereof after extraction to a fractionating step, and cracking a fraction resulting from further fractionating. X 1310

45. 5. In the treatment of a product of the partial oxidation of mineral oil containing a plurality of different oxygen derivatives of aliphatic hydrocarbons in the range from alcohols to oxygenated acids, the steps consisting of fractionating the product into at least three fractions, reacting with a chemical to extract a chemical product from a lighter fraction, returning a remainder thereof after extraction to a fractionating step, removing a heavier fraction, and cracking an intermediate fraction.

55. 6. In the treatment of a product of the partial oxidation of mineral oil containing a plurality of different oxygen derivatives of aliphatic hydrocarbons in the range from alcohols to oxygenated acids, the steps consisting of fractionating the liquid product, reacting with a chemical to extract a chemical product from a lighter fraction, returning a remainder thereof after extraction to a fractionating step, removing a heavier fraction, and extracting a chemical product from said heavier fraction.

65. 7. In the treatment of a product of the partial oxidation of mineral oil containing a plurality of different oxygen derivatives of aliphatic hydrocarbons in the range from alcohols to oxygenated acids, the steps consisting of fractionating the liquid product, reacting with a chemical to extract a chemical product from a lighter fraction,

returning a remainder thereof after extraction to a fractionating step, cracking a heavier fraction, and fractionating the product of said cracking.

8. In the treatment of a product of the partial oxidation of mineral oil containing a plurality of different oxygen derivatives of aliphatic hydrocarbons in the range from alcohols to oxygenated acids, the steps consisting of fractionating the liquid product, extracting a chemical product from a lighter fraction, returning a remainder thereof after extraction to a fractionating step, cracking a heavier fraction, fractionating the product, and extracting a chemical product from a fraction obtained in the latter fractionating of the cracked fraction.

9. In the treatment of a product of the partial oxidation of mineral oil containing a plurality of different oxygen derivatives of aliphatic hydrocarbons in the range from alcohols to oxygenated acids, the steps consisting of fractionating the product, reacting with a chemical to extract a chemical product from a fraction, adding the remainder of said fraction to another fraction, cracking the combined portions thus obtained, extracting motor fuel from the cracked product, and reoxidizing a remainder from the latter extraction of motor fuel from the cracked product.

10. In the treatment of a product of the partial oxidation of mineral oil containing a plurality of different oxygen derivatives of aliphatic hydrocarbons in the range from alcohols to oxygenated acids, the steps consisting of fractionating the product, reacting with a chemical to extract a chemical product from a lighter fraction, adding a remainder thereof after extraction to a heavier fraction, cracking the combined portions, recovering motor fuel from the cracked product, and reoxidizing a remainder from said recovery.

11. In the treatment of a product of the partial oxidation of mineral oil, the steps consisting of removing a lighter portion, cracking a portion heavier than said lighter portion, and polymerizing bodies passing off in gaseous state from the cracking step.

12. In the method of obtaining a plurality of different chemical products from normally liquid partially oxidized petroleum containing oxygenated acids and other oxygen derivatives in the range from alcohols to acids, the steps consisting of removing acids from substantially all portions thereof and fractionating the petroleum into at least three portions, separating a lighter portion, recovering a chemical from said lighter portion, separating a heavier portion, reacting it to recover a chemical product therefrom, and cracking an intermediate portion.

13. In the method of obtaining a plurality of different chemical products from normally liquid partially oxidized petroleum containing oxy-

genated acids and other oxygen derivatives in the range from alcohols to acids, the steps consisting of first removing acids from said product, then fractionating the product into at least three portions, separating a lighter portion, recovering a chemical from said lighter portion, separating a heavier portion, reacting it to recover a chemical product therefrom, and cracking an intermediate portion.

14. In the method of obtaining a plurality of different chemical products from partially oxidized petroleum containing oxygenated acids and other oxygen derivatives in the range from alcohols to acids, the steps consisting of first removing acids from said product, then fractionating the same into at least three portions, separating a lighter portion, recovering a chemical from said lighter portion, separating a heavier portion, reacting it to recover a chemical product therefrom, and cracking an intermediate portion containing a part of said heavier portion.

15. In the method of obtaining a plurality of different chemical products from partially oxidized petroleum containing oxygenated acids and other oxygen derivatives in the range from alcohols to acids, the steps consisting of first removing acids from said product, then fractionating the same into at least three portions, separating a lighter portion, recovering a chemical from said lighter portion, separating a heavier portion, reacting it to recover a chemical product therefrom, and cracking an intermediate portion containing parts of both the lighter and heavier portions.

16. In the method of obtaining a plurality of different chemical products from normally liquid partially oxidized petroleum containing oxygenated acids and other oxygen derivatives in the range from alcohols to acids, the steps consisting of first removing acids from said product, then fractionating the product into at least three portions, separating a lighter portion, recovering a solvent from said lighter portion, separating a heavier portion, reacting it to recover a chemical product therefrom, and cracking an intermediate portion.

17. In the method of obtaining a plurality of different chemical products from normally liquid partially oxidized petroleum containing oxygenated acids and other oxygen derivatives in the range from alcohols to acids, the steps consisting of first removing acids from said product, then fractionating the product into at least three portions, separating a lighter portion, recovering a chemical from said lighter portion, separating a heavier portion, reacting it to recover a detergent therefrom, and cracking an intermediate portion.

JOSEPH HIDY JAMES.
